UNITED STATES PATENT OFFICE.

ISIDOR M. JACOBS AND WILLIAM CRAMER, OF ST. LOUIS, MISSOURI, ASSIGNORS TO TRUCK TRACTOR & MANUFACTURING COMPANY, OF ST. LOUIS, MISSOURI, A CORPORATION OF MISSOURI.

BELT-FASTENING DEVICE.

Application filed February 23, 1923. Serial No. 620,854.

To all whom it may concern:

Be it known that we, ISIDOR M. JACOBS and WILLIAM CRAMER, citizens of the United States of America, and residents of the city 5 of St. Louis and State of Missouri, have invented certain new and useful Improvements in Belt-Fastening Devices, of which the following is a full, clear, and exact description, reference being had to the accompanying drawings, forming a part of this 10 specification.

This invention relates to improvements in belt fastening devices of the type used to apply metallic belt lacings to power transmission belts for the purpose of securing the 15 ends of said belts together, and particularly to a device of the type mentioned which is provided with a cutting device for trimming the end portions of the belts to be acted on.

20 Prior to this invention belt fastening devices of the type mentioned above have been provided with cutting devices, but due to certain deficiencies therein said cutting devices have not always functioned in an 25 entirely successful manner. For the ends of a power transmission belt to be connected together in a manner to provide a very secure joint, it is necessary that the meeting faces of the end portions of said belt be cut at 30 right angles relative to the top and bottom faces of said belt, but in the use of the cutting devices heretofore used this was not always possible, due to the fact that it was 35 possible for the belt to move slightly during the cutting operation whereby the end portions of said belt were provided with meeting faces which were not cut at the proper angles.

40 The belt fastening device disclosed in the present application is provided with a cutting device which is so arranged that the belt will be prevented from moving with relation to the knife blade during the cutting operation whereby the objections recited 45 above are eliminated.

With the foregoing and other objects in view, the invention comprises the novel construction, combination and arrangement of parts hereinafter more specifically described 50 and illustrated in the accompanying drawings wherein is shown the preferred embodiment of the invention. However, it is to be understood that the invention comprehends

changes, variations and modifications which come within the scope of the claims hereunto 55 appended.

Fig. I is a perspective view of our improved belt fastening device showing the cutting device associated therewith.

Fig. II is a longitudinal section through 60 the fastening device shown in Fig. I.

Fig. III is a section on line III—III of Fig. I.

Fig. IV is an enlarged fragmentary section showing the cutting mechanism of our 65 improved belt fastening device.

In the drawing, A designates our improved belt fastening device which comprises an anvil B, staple-holding mechanism C and a hammer D. The anvil B is preferably formed of comparatively heavy metal 70 and is provided with a plurality of reinforcing ribs B' which are intended to add durability to said anvil. The anvil B is provided at one of its ends with a head portion 75 E.

Mounted on the anvil B immediately above the head portion E is the staple holding mechanism C, said mechanism comprising a plate 1 which is secured to the anvil B preferably by means of rivets 2. The plate 1, as shown in Fig. I, extends approximately the full width of the anvil B and said plate is provided with a plurality of slots 3 formed along the front edge of said plate. Formed through each of the tooth-like portions 4 of the plate 1 is an opening, all of said openings being in alinement so that an opening is formed which extends from end to end of said slotted portion of said plate 1. Extended through the openings referred to above is an elongated pin 5, said pin being preferably provided with a loop at one of its ends to provide a convenient means for withdrawing said pin from said openings. 95

The hammer D of our improved belt fastening device comprises a head portion 6 and a pair of arms 7 which are preferably formed integral with said head portion 6. The hammer D is pivotally secured to the anvil B of my improved belt fastening device, there being a rod 8 which extends laterally through the head portion E of the anvil B and projects from each side face of said head portion E, which projecting portions of said rod pass through openings in 100 105

the arms 7 of the hammer whereby said hammer is arranged to swing in an arc of a circle about said rod 8.

The cutting device of our improved belt fastening device is designated in the drawing by the reference character F, and comprises an L-shaped member 9 which is secured to the anvil B by means of rivets 10 which pass through said anvil B and through the horizontal leg of the member 9 (Fig. IV). The vertical leg of the L-shaped member 9 is spaced apart from the side face of anvil B. Pivotedly mounted on the rod 8 is a knife blade 11, said knife blade being arranged to operate in the space between a side face of the anvil B and the inside face of the vertical leg of the L-shaped member 9. The space within which the knife blade 11 operates is of such width that said knife blade fits tightly between the adjacent faces of the anvil and the vertical leg of the member 9, hence, due to the friction exerted against the knife blade, said knife blade will remain in any position in which it is placed.

25 The operation of our improved belt fastening device is as follows:

Assuming that it is desired to secure the ends of a power transmission belt together, it is first necessary to trim the end portions 30 of said belt so that the meeting edges thereof will be provided with faces which are cut at right angles to top and bottom faces of said belt, and also that said meeting edges are cut at right angles to the side edges 35 of said belt. The anvil B, as will be noted by referring Fig. I, is provided with an upstanding flange 12 at each of its side edges, and an upstanding abutment 13 at its front end, said abutment 13 being higher 40 than the flanges 12. It will also be observed by referring to the same view that the anvil B is provided with an intermediate rib 14 which is of the same height as the flanges 12. In use, the belt to be trimmed 45 is placed laterally of the anvil B so that the portion to be cut from said belt extends beyond the cutting edge of the knife blade 11, and so that a side edge of said belt rests against the inside face of the upstanding 50 abutment 13 in which position said belt will be supported by the flanges 12 and rib 14, so that it may not sag. The fact that a side edge of the belt is contacting with the abutment 13 will insure a cut edge which is at 55 a right angle to the side edges of the belt. When the belt has been arranged in the position described the knife blade 11 is struck a hammer blow, and said blade is driven through the belt to sever same.

60 It will be noted by reference to Fig. IV that the belt extends across the space within which the knife blade 11 operates and

that said belt is supported on either side of said space by one of the flanges 12 and by the vertical leg of the L-shaped member 9, hence when the knife blade 11 moves through said belt there will be no opportunity for said belt to move relative to said knife, whereby a vertical cut is made in said belt which is a true right angle to the top and bottom faces of said belt. It is, of course, apparent that the flange 12 is provided with a cutting edge 15 which cooperates with the cutting edge of the knife blade 11 to sever the belt.

After the belt has been trimmed in the manner described the elongated pin 5 is withdrawn from the openings through which it extends, and a staple 5 is inserted into each of the slots in plate 1 or into as many of said slots as is necessary, depending on the width of the belt to be acted on. The elongated pin is then again inserted through the openings in a manner to lock said staples in said slots (Fig. II). An end of the belt is then inserted between the sharpened ends of the staples S in the manner illustrated in Fig. II, when the hammer D is brought to a position where the head thereof rests on the upper legs of the row of staples, and said hammer is struck a blow which will drive the ends of said staples into the belt and clinch same. After both ends of the belt have been provided with staples in the manner described, the staples of the opposite ends of said belt are connected together in the well known manner.

When the belt is placed in position to be laced the abutment 13 will support said belt so that the end to be laced will drop onto the anvil in position to receive the staples.

We claim:

A belt fastening device comprising an anvil, staple holding means, upstanding marginal belt supporting members on said anvil, an intermediate belt supporting member disposed between said marginal belt supporting members, one of said marginal belt supporting members forming a shear for a belt supported by said supporting members, a pivoted knife cooperating with the shear member, and an upstanding abutment at the outer edge of said anvil adapted to support a belt so that the end of said belt will drop onto the anvil in position to receive the staples, and said abutment adapted to act as an aligning abutment during the cutting operation.

In testimony that we claim the foregoing we hereunto affix our signatures.

ISIDOR M. JACOBS.
WILLIAM CRAMER.
